UNITED STATES PATENT OFFICE

WILLIAM H. SMITH, OF MOBILE, ALABAMA

RAIL JOINT

Application filed January 7, 1929. Serial No. 330,716.

This invention relates to railroad track appliances and in particular to the construction of joints between rail sections, having for its primary object the provision of an improved and novel rail joint connection.

Other objects of the invention are: to provide in a rail joint a novel means for preventing creeping between adjacent rail sections; to provide an improved rail joint having novel means for providing substantially uninterrupted continuity of tread surface; and generally to provide a novel structural arrangement of rail sections cooperating to provide a rail joint.

15 In the drawings: Figure 1 is an elevation of a rail joint as set up in accordance with the principles of the invention.

Figure 2 is a top plan view thereof.

Figure 3 is a vertical section on the line 20 3—3 of Figure 2.

Figure 4 is a perspective of the fish plate at one side of the joint as illustrated in Figure 1.

The present conventional practice in this art provides mainly for connecting rail sections with transverse joints, that is, with the meeting ends of the adjacent rail sections lying in planes at right angles to the rail sections. Due to such a construction there is an inevitable wear at the meeting edges of the rail sections, which in time causes breakage and results in a constant pounding and clicking of wheels passing over such a joint. The present invention has been designed to eliminate these objectionable characteristics of the present conventional rail joint, and with the above enumerated objects in view, a preferred form for carrying out the principles of the invention is herein shown and described.

In rail joints constructed in accordance with my invention, the adjacent ends 5 and 6 of railroad rail sections which are to be connected together are formed so that instead of having ends lying in planes at right angles to the body of the rail, each of the sections has its end cut on a diagonal line extending across the rail which provides angled ends 7 and 8 respectively upon the sections. The angled ends 7 and 8 of the two adjacent sec-

tions 5 and 6 are disposed with their inclined faces arranged in opposite angles of inclination and the sections terminate in slightly spaced relation so that the entire area between the ends of the rail sections is 55 adapted to receive a connecting block 9 which is formed as a continuation of the rail construction and is provided with inclined end faces 10 and 11 adapted for engagement with the respective end faces 7 and 8 of the adjacent sections 5 and 6.

At its central portion the connector block 9 has a width equal to the full width of the adjacent rail sections so that the central portion of the connector block completely 63 fills the space between the terminal portions of the adjacent rail sections providing for an uninterrupted continuity of rail surface. The connector block 9 is formed adjacent each end with a laterally outstanding lug 12 carried by the web portion of the block, both of which extend from the same side of the block and are adapted to cooperate with similar lateral lugs 13 and 14 respectively carried by the rail sections 5 and 6. At the 75 opposite side of the rail the block 9 carries a central laterally extending lug 15 disposed and cooperating with lateral lugs 16 and 17 respectively carried by the adjacent terminal portions of the rail sections 5 and 6. All of 80 the respective webs of the rail sections and body of the connector block are suitably apertured to receive therethrough the desired number of securing bolts 18 which are secured by the usual nuts 19 after having been 85 positioned through fish plates 20 and 21 disposed at opposite sides of the rail.

One of these fish plates, 21, is shown in perspective in Figure 4 wherein it will be noted that the body 21 is formed to the outline of the joint having outstanding socket portions 22 which are adapted to receive the respective lug pieces 12, 13 and 14 of the rail sections and connector block. At the opposite side of the rail the fish plate 20 is 95 formed to conform with that side of the joint having a central socket portion to receive the respective lug pieces 15, 16 and 17 previously described.

These respective lug pieces not only pro-

vide a means for preventing longitudinal creeping between the respective joint elements when in assembled relation, but they cooperate with the web of the rail section upon which they are provided so as to maintain the uniform thickness of the web throughout the entire joint, as best shown in dotted lines in Figure 2. By reason of this construction the inclined ends of the rail sections 5 and 6 are not weakened at the points where they taper off substantially to a feather edge. It will be noted that by reason of the present construction there is no transverse break at the joint connection and the meeting edges of the sections and connector block are disposed at a gradual angle across the rail tread surface so that the relative continuity of the rail tread is substantially uninterrupted at the joint.

20 I claim:

1. In a rail joint, rail sections having their adjacent ends formed at an angle, a connector block formed for engagement between the ends of adjacent sections to provide continuity of rail tread surface, abutting stop members carried by said sections and connector block and extending laterally respectively therefrom, and fish plates formed to receive said stop members in socket recesses provided in the body thereof.
2. In a rail joint, rail sections having their adjacent ends disposed in spaced relation and cut at an angle relative to the longitudinal axis of the rail, a connector block having its opposite ends angled in conformity with the adjacent ends of the rail sections and formed to fill the entire area between the respective rail sections, fish plates cooperating with said joint at opposite sides thereof, and laterally projecting lug members formed on said rail sections and connector block for engagement in portions of said fish plates.

In testimony whereof, I affix my signature.
WILLIAM H. SMITH.
